UNITED STATES PATENT OFFICE.

HENRY B. MORRIS, OF ITHACA, NEW YORK, ASSIGNOR TO THE AUTOPHONE COMPANY, OF SAME PLACE.

MACHINE FOR MAKING AND INSERTING STAPLES IN MUSIC-ROLLERS.

SPECIFICATION forming part of Letters Patent No. 339,679, dated April 13, 1886.

Application filed October 8, 1885. Serial No. 179,371. (No model.)

To all whom it may concern:

Be it known that I, HENRY B. MORRIS, a citizen of the United States, residing at Ithaca, in the county of Tompkins and State of New York, have invented a certain new and useful machine for inserting wire cams or staples at predetermined points into rollers intended for use in mechanical musical instruments, of which the following is a specification.

10 The leading characteristic of the machine is an intermittently-moving pattern which governs the insertion of the staples and determines their length.

As is well known, the shortest notes of such 15 mechanical musical instruments as hand-organs, orchestrions, &c., are produced by single pins projecting from the surface of a slowly-turning cylinder, which operate upon keys or valves to produce the tones. Longer notes 20 must be made by cam-surfaces upon the roller, of suitable length, so as to hold the keys or valves open for the proper time. Such a cam is commonly made of a wire bent into the form 25 of a staple, its two points being inserted into the roller, and its middle projecting part being concentric with the surface thereof. The preparation of such staples of many various 30 lengths and their correct insertion into the roller is a work requiring much labor and skill, and rollers so prepared are very expensive.

The object of this invention is to provide 35 mechanical means for making such staples and for driving them into the roller automatically and without the intervention of skilled labor.

In order that my invention may be clearly 40 understood, I have illustrated and will proceed to describe a practical form of a machine adapted to insert staples in a wooden roller along a spiral line.

Figure 1 is a plan view of the machine. Fig. 45 2 is a vertical longitudinal section in the plane indicated by the broken line 11 of Fig. 1. Figs. 3 to 10 illustrate details of the machine, some being drawn on a larger scale than Figs. 1 and 2, and others on the same scale. Fig. 11 is a plan view, partly in section, of the roller-carriage and its attachments, the section being taken upon the dotted line 2, Fig. 2.

The same letters of reference indicate identical parts in all the figures.

The various parts of the machine are mounted on a suitable bed-plate or table, A, provided with the shear *a* across one end, for the support and guidance of the rear side of a sliding carriage, consisting of the upright 55 cheek-plates B B' and the parallel connecting-bars B² B³ B⁴. The front side of the carriage is supported and guided by the bar C, parallel with the shear *a*, said bar passing through holes in the cheek-plates B B', and being itself 60 supported and held by the lugs C' C' on the bed plate A, into which it passes. A horizontal roller, D, provided with projecting hubs at its ends, is arranged in suitable bearings between the cheek-plates of the carriage, 65 said hubs projecting through the cheek-plates B B' and forming the journals of the roller. The parts of the hubs passing through the cheek-plates are smaller than those adjoining the roller, thereby forming shoulders upon said hubs, 70 which prevent any lateral motion of the roller between the cheek-plates. The hub D' projects beyond the cheek-plate B', and upon its outer end is rigidly attached the spur-wheel E. A shaft, F, journaled in the fixed bearing F' 75 on the bed-plate, passes through the hub D' into roller D, which is bored nearly its whole length to fit the shaft. A keyway, *f*, is cut in that part of shaft F which passes into the roller and hub, and the hole through which 80 it so passes is provided with a corresponding spline, so that while said roller is turned by the shaft it may, with the carriage and the spur-wheel E, move longitudinally thereon. The hub at the end opposite that entered by shaft F is tapped or provided with a fixed nut to fit 85 upon the screw H, which passes through the hub into the roller nearly far enough to meet the end of shaft F. The outer end of the screw is rigidly secured to a standard, H', on the 90 bed-plate A, or it may be so arranged as to be fastened and loosened at pleasure, so that the roller and carriage may be slid along the ways by revolving the screw when the machine is at rest. Two rings, G G', of steel or other 95 hard metal, about equal in diameter to the roller D, are rigidly attached thereto at its opposite ends. The outer surface of the rings is roughened by fine flutes formed therein parallel with their axis. Upon the surface of the 100

roller between the rings is formed a deep square-shaped screw-thread, D^2 , of the same pitch as the screw H . A longitudinal groove, D^3 , is also formed in the roller, extending from ring G to ring G' , said groove being much deeper than screw-threads D^2 , which it intersects. Two parallel bars, $I' I^2$, are fitted into the groove D^3 , and there secured by screws at their ends, which screw into the roller. The outer surface of bars $I' I^2$ is curved, being flush and concentric with the top of screw-threads D^2 .

I is a pattern-belt, preferably made of a sheet of steel, which tightly encircles the roller D , and is riveted or otherwise secured by its ends to the bars $I' I^2$, the body of the pattern-belt resting upon the tops of screw-threads D^2 . The pattern-belt is pierced with a series of holes, which govern the position and length of the staples to be driven into the music-roller; hence a separate pattern is required for each different kind of music-roller to be produced, and said pattern may be readily changed by unscrewing the bars $I' I^2$, removing them with the belt I attached, and replacing them by another similar pair of bars, to which is fastened a different pattern-belt. A live-spindle, K , is journaled in the upper portion of cheek-plate B' . This spindle carries a disk, K' , at its inner end, and at the opposite end a fixed spur-wheel, L , of the same diameter and number of teeth as spur-wheel E , which drives it through the medium of an intermediate spur-wheel, L' . The disk K' is provided with a center pin, and also with a drive-pin, K^2 . Cheek-plate B carries in its upper portion a dead-center, K^3 , screwed in the cheek-plate, so that it may be adjusted. The wooden roller M , in which the staples are to be inserted, and which I term the "music-roller," is centered on dead-center K^3 and central pin of disk K' , one end of the roller being bored with an eccentric hole to receive the drive-pin K^2 . It will be seen that the turning of shaft F has the twofold effect of feeding the carriage, together with the rollers D and M , and of revolving said rollers synchronously, so that they complete a rotation in the same time.

The devices for cutting and forming the staples and inserting them in the music-roller are mounted upon the stand N , erected on the bed-plate. A sliding head, O , is mounted upon the stand, sliding in a dovetail groove formed in the top of said stand, in a direction parallel with the axis of the music-roller. The sliding head carries two sliding blocks, O' , O^2 , which are fitted to parallel dovetail grooves in the top of said sliding head. Said sliding blocks move horizontally in a direction at right angles with the axis of music-roller. A vertical die-plate, P , is rigidly secured to the sliding head O on the side nearest the music-roller. In one side of the die-plate, near the top, is formed a notch whose lower side is horizontal, the upper side being inclined, preferably at about thirty degrees

to the lower. Plate P is provided with a horizontal ledge of metal, p , on one side, the upper side of which ledge is even with lower side of notch.

Attached to the sliding block O' , is a triangular punch, P' , two edges of which fit the notch in die-plate P . The wire R , to be made into staples, is fed from a reel overhead, vertically downward, by a pair of feed-rolls, $R' R^2$, mounted upon a standard, R^3 , erected on the bed-plate, said rolls being driven through the medium of a pulley, R^4 , and a belt, by a pulley on the shaft S' . The feed-rolls do not press very tightly upon the wire, so that when its advancing end strikes the ledge p its further progress is for the time prevented, the rolls revolving without advancing the wire, which, to prevent it from being bent, may, when necessary, be conducted through a small guide-tube nearly as far as the upper side of the notch in the die-plate. The sliding block O^2 is provided with a transverse dovetail groove near one end, in which a block, O^3 , slides horizontally, said block having a swage-plate, O^4 , rigidly attached to it. One end of the swage-plate projects nearly across the face of punch P' , and is beveled at same angle as the punch and notch in die-plate. The end of the punch is recessed to receive the swage-plate, the bottom of said recess being curved, as is also the swage-plate, to the shape required to make the staples concentric with the music-roller when driven. The normal position of swage-plate is in about the same plane as the die-plate P .

The process of forming and driving a staple is as follows: When the block O' is moved forward, the punch P' cuts off the portion of wire extending across the notch in die-plate, pressing it at the same time against swage-plate O^4 , to prevent it from flying away. The further advance of the punch causes the swage-plate O^4 to force the wire back into the recess in the face of the punch, bending it into the required shape, as is fully shown in Fig. 8. The staple is firmly held between the swage-plate and punch, which advance together toward the music-roller, the block O^2 being now driven by block O' by means of stud O^5 , rigidly attached to block O' , and projecting into a slot in the side of block O^2 , said slot and stud being so arranged that the block O^2 shall begin to move just as the staple has been formed between the punch and swage-plate, in the manner just described, and also that the block O^2 shall not be withdrawn beyond its normal position by the retreat of block O' . When the staple has been advanced so far that its ends have entered the wooden roller beyond danger of its escape, the swage-plate O^4 is suddenly withdrawn by means of the lever O^6 centrally pivoted on block O^2 , having one end engaged with sliding block O^3 , and being actuated by the stationary pin O^7 upon the head O , which pin is struck by the outer curved end of the lever as the same advances with its block O^2 . The punch P' now contin-

ues its advance until it has inserted the staple to a certain depth into the music-roller, when it is withdrawn by retreat of block O' to the place of beginning, the swage-plate O⁴, block 5 O³, and lever O⁶ returning to their normal positions, being influenced by the spring O⁸, attached to block O², acting upon the lever. More wire is now advanced by the feed-rolls and the punch is ready for another stroke. 10 It should be remarked that the block O³ slides rather tightly in its groove, thus causing sufficient pressure between the swage-plate and punch to insure the bending of the wire into the staple required. Since the wire is fed by 15 the feed-roll always in the same line, and all the staple-forming devices above described may be moved laterally by sliding the head O, which carries them, it follows that wires of different lengths may be cut by the beveled 20 punch P' and its corresponding die, depending for their length upon the position of sliding head O, and as the swage-plate O⁴ is also beveled the shanks of the staples when formed will all be of equal length, so that their outer 25 curved portion alone will vary. Moreover, if the head O remain stationary after the wires are cut and while the staples are being driven, they will always be driven into the roller in the fixed plane of the feed-wire R.

30 I will now proceed to describe the means whereby the insertion of the staples is governed by the perforated pattern-belt. A line of shafting extends across the end of the bed-plate opposite the roller-carriage, being suitably journaled in standards erected upon the bed-plate. This shafting consists of two independent portions, S S', arranged in the same line, their place of separation being indicated by the dotted line S², Fig. 1. At the junction 35 of the shafts S S' is a clutch consisting of a disk-plate, S³, fixed upon the end of shaft S, and upon shaft S' a larger circular plate, S⁴, provided with an overhanging flange which encircles disk-plate S³. A block, T, moves 40 radially in a groove in the outer side of plate S³, being forced outwardly by an elliptic spring, T', acting against a pin, T², fixed in the block. A radial notch, T³, is cut through the flange 45 of plate S⁴, so that when block T is pushed outward by the spring it enters notch T³ and locks the plates together, causing them to revolve as one. The shaft S and plate S³ are revolved continuously by suitable motive power applied at the opposite end of shaft S, but 50 shaft S' remains at rest when the block T is forced centrally and prevented from engaging the notch T³. This is effected by the clutch-bar T¹, centrally pivoted upon a standard attached to the bed-plate and operated by means hereinafter to be explained. 55 The clutch-bar T¹ oscillates vertically and bears downward upon the pin T² of clutch-block T, so that when said bar is in its normal position, as shown in Fig. 3, the block is 60 prevented from engaging with slot T³. As the block T revolves, being carried around by disk S³, its centrifugal motion is prevented during

most of its course by the overhanging flange of disk S³; but when it arrives near the top the bar T¹, acting upon pin T², forces the block 70 farther in toward the center of disk than is needed to prevent its entering slot T³; hence the bar T¹ may be elevated to a certain distance without allowing the clutch to lock. At each revolution of disk S⁴ a cam, S⁵, fixed 75 thereon strikes a pin, T⁵, on bar T¹, thereby depressing the bar beyond its normal position and immediately releasing it. The clutch-bar is connected at its opposite end by the vertical connecting-rod U with the rock-arm U', 80 attached to rock-shaft U². Another rock-arm, U³, is fixed upon said rock-shaft diametrically opposite U', and is connected by means of vertical connecting-rod U⁴ with the feeler-bar V, near the middle of said feeler-bar. A stand- 85 ard, W, is erected on the bed-plate, to the upper part of which one end of feeler-bar V is pivoted, so that said bar may oscillate vertically.

Rigidly attached to the feeler-bar near its 90 free end is the feeler, consisting of a short cylindrical bar, V', preferably of hardened steel, having upon its lower end a smaller cylindrical part, V², which I call the "point." When the machine is not inserting staples, the point 95 V² rests upon the pattern-belt I on roller D, being pressed downward by a spring, U⁵, on the bed-plate, which acts upon lower end of rod U⁴, and through it influences the feeler-bar V and all its connections just described— 100 namely, rock-arms U³ U', rock-shaft U², rod U, and clutch-bar T¹. This mechanism is so arranged that when the point V² is resting upon the pattern-belt the clutch-bar is in its normal position, Fig. 3.

Upon the continuously-revolving shaft S is a small tight pulley, X, which transmits motion by the belt X' to a large pulley, X², turning loosely upon the roller-shaft F, and having a large central hub, X³. The hub X³ is confined 110 between two circular friction-plates, F² and F³, upon shaft F, plate F² being rigidly attached to shaft, and plate F³, fitting loosely on the end thereof, being prevented from turning on the shaft by a spine. The hub X³ is compressed 115 between friction-plates by means of a capped spring, F⁴, held and regulated by a screw passing centrally through said spring into the end of shaft F. Friction is thus produced between the hub and friction-plates sufficient 120 to cause shaft F to be turned by pulley X², except when otherwise prevented.

The perforations in the pattern-belt I consist each of a narrow parallel-sided slot, J, of predetermined length, terminating in a large 125 circular hole, J'. Said perforations are so located as to be directly over the grooves between the screw-threads D² of the roller D.

As before explained, the screw-threads D², formed upon the surface of the roller D, are of the same pitch as the feed-screw H. The feeler-point V² is situated directly over the spiral groove between the screw-threads on the roller.

The object of grooving the roller D spirally,

105

110

115

120

125

with the same pitch as the feed-screw, is that as said roller is fed along the screw H by its revolution thereon the screw-threads D² shall maintain their relative position to the feeler-point V², the groove between two of said threads being always directly under the feeler-point. This would not be the case if the threads D² were of a pitch different from that of the feed-screw. The groove in the pattern-roller being thus always under the point affords the latter sufficient depth for its required descent through the holes in the pattern-sheet.

In operating the machine, the shaft F being turned, the rollers D and M are revolved and the carriage is fed along its guides. The feeler-point V² rests upon the pattern-belt, describing a spiral course thereon. When the feeler encounters a perforation in the belt, the point V² at once descends into the narrow slot J as far as permitted by the larger part V' above. The feeler-bar V also descends, and through its connection therewith the clutch-bar T⁴ is moved, so that the end of clutch-bar adjoining the clutch is elevated, not far enough, however, to permit the block T to engage the slot T³; hence the clutch is not yet locked and the shaft S' remains at rest. The feeler-bar is provided with a hook, Y, on its under side, supporting a horizontal rod, Y', parallel with the roller D. The ends of rod Y' are attached to two pawls, Y³ Y⁴, said pawls being centrally supported on studs in the cheek-plates of the carriage, which studs pass through central longitudinal slots in said pawls. Another rod, Y⁵, parallel with Y', connects the pawls Y³ and Y⁴ at their opposite ends, the two rods and the pawls thus forming a rigid frame. The ends of the pawls adjoining rod Y' are adapted to engage the fluted rings G G' on roller D. While the feeler-point V² rests upon the pattern-belt I the pawls Y³ Y⁴ are held up by the hook Y out of gear with the fluted rings; but when the feeler-bar V is depressed by the descent of the point into a slot, J, said pawls, being thus lowered, engage with the flutes in said rings, and are moved longitudinally by the continued rotation of roller D, the rod Y⁵ striking and driving before it the slotted cam-bar Z. This cam-bar is provided with a longitudinal slot near one end, which end is supported by a stud, Z', fixed in standard W. The opposite end of cam-bar is beveled to correspond with a cam, Z², attached to the sliding head O, and is supported and held against said cam by a shouldered stud, Z³, erected on the bed-plate. When by the progress of the roller D the point V² reaches the end of slot J, the thicker portion V' of the feeler enters large hole J', the point descending into the spiral groove between screw-threads D². This brings the friction-driven rollers D and M to a standstill, the additional depression of feeler-bar V resulting, through its connections with the clutch-bar T⁴, in locking the clutch and the rotation of shaft S'. A staple is now formed and inserted in the music-roller, the block O' being advanced and

retracted by an eccentric, S⁶, on shaft S', which actuates said block through the medium of the eccentric-rod S⁷, rock-arm S⁸, wrist S⁹, and connecting-rod S¹⁰. The wrist S⁹ is prolonged so that the engaging-eye of rod S¹⁰ may move lengthwise upon it when carried by sliding head O, the opposite end of rod being snugly pivoted to block O'. When a staple has been inserted, the cam S⁵ strikes pin T⁵, momentarily depressing it so far that through their intermediate connections the feeler-point V² is raised clear above the surface of the pattern-belt, which, being no longer restrained by the feeler, at once proceeds to revolve. The point V² is quickly allowed to drop upon the pattern-belt, and all the parts of the machine connected with it resume their normal positions, the sliding head O being returned by a spring, O', upon standard N, and the cam-bar Z by spring W' on standard W. By the elevation of the feeler-bar V the hook Y withdraws the pawls Y³ Y⁴ from contact with fluted rings G G', and the pawls are driven back to their first position by the retreat of the cam-bar.

It is obvious from the foregoing description that so long as the feeler-point rests upon the imperforate portion of the pattern-belt the friction-driven rollers D and M revolve and the staple-forming devices remain at rest; also, that the descent of the feeler V' into a large hole, J', causes the rollers to stop and the staple devices to operate. It is furthermore plain that the entrance of the feeler-point into a slot, J, results in sliding the head O. Since the length of a staple depends on the position of head O, as before explained, and this in turn depends upon the distance to which the cam Z² and cam-bar are moved by the pawls Y³ Y⁴, it follows that the presence of a long slot, J, in the pattern-belt will cause more motion of the head O than a short slot would do, and consequently the formation of a longer staple; hence the length of each staple will be in direct proportion to the length of its corresponding slot in the prearranged pattern-belt. The punch P' does not drive the staples quite to their destined depth in the music-roller, thereby avoiding the danger of driving too far any previously-driven staples with which it may come in contact, but all the staples may be subsequently reduced to a proper depth by revolving the music-roller in another machine against a hardened pressure-roller, or by any other convenient method.

In order to perform most pieces of music, single pins are required upon the music-roller as well as staples. Such pins may be inserted before or after the staples, either by hand or by automatic machinery—such, for instance, as that for which Letters Patent were granted to me April 7, 1885, No. 315,052—or the pin-driving devices therein described may be combined with this machine, so that a roller may be furnished with both pins and staples by the same machine. This I regard as a mere modification of my invention, and

many other variations may be made without departing from the principles of my invention. For instance, to adapt the machine for preparing rollers having circular rows of staples and pins, the screw-feed may be so modified as to advance the carriage a distance equal to that between two adjacent rows at the completion of each full turn of the pattern-roller, parallel circular grooves being substituted for the spiral grooves in said roller.

I believe that I am the first to provide a machine for automatically inserting staples in music-rollers in accordance with a previously-prepared and intermittently-moved pattern, and therefore claim such machine broadly.

As regards the pattern, its form may be much varied. Thus, instead of using a changeable pattern-belt upon a roller, a separate roller may be provided for each kind of music-roller having depressions corresponding with the perforations, or the pattern may consist of a plane surface with perforations or depressions, suitable changes being made in the feeler and other connections.

I claim as my invention—

1. A machine for making and inserting staples in music-rollers, organized with an intermittently-moved pattern, which governs the length and position of the staples, substantially as described.

2. A machine for making and inserting staples in music-rollers, organized with an intermittently-moved pattern, which governs the position and length of the staples, said pattern being moved by a friction-feed, substantially as set forth.

3. In a machine for making and inserting staples in music-rollers, the combination, substantially as set forth, of the feed-carriage, feed-screw, and pattern-roller, the said roller having its surface spirally grooved with the same pitch as the feed-screw.

4. In a machine for making and inserting staples in music-rollers, the combination, substantially as and for the purposes set forth, of a grooved pattern-roller with a perforated pattern-belt, said belt encircling the roller and having its perforations opposite said grooves.

5. The combination, substantially as described, of a perforated pattern-belt encircling a friction-driven roller, with a feeler-point arranged to press upon said pattern-

belt and to detain the roller by engaging with a perforation in said pattern-belt.

6. The combination, substantially as before set forth, of the intermittently-moved pattern-roller, the perforated pattern-belt, the feeler, the staple-driver, and means controlled by the feeler for reciprocating the staple driver.

7. The combination, substantially as before set forth, of the perforated pattern-belt, the feeler, the revolving cam S^5 , and means controlled by the cam for elevating the feeler above the pattern-belt.

8. In a machine for making and inserting staples in music-rollers, the pattern-belt pierced with parallel-sided slots J , said slots corresponding in length with the staples to be formed, substantially as set forth.

9. The combination of the perforation in the pattern-belt, consisting of the parallel-sided slots J , terminated by the larger holes J' , with the feeler, composed of a point, V^2 , of small diameter, and a part, V' , of greater diameter, said devices being constructed and arranged with reference to each other, and operating substantially as and for the purposes set forth.

10. In a machine for making and inserting staples in music-rollers, the sliding head O , supporting the staple forming and driving devices, the head having a reciprocating motion, substantially as and for the purposes described.

11. The combination, substantially as set forth, of the intermittently-moved pattern-roller, the sliding head O , and means actuated by the pattern-roller for moving the sliding head.

12. The combination, substantially as described, of the intermittently-moved pattern-roller, the perforated pattern-belt, the feeler, the sliding head O , and means controlled by the feeler for governing the motion of the sliding head.

13. In combination with the sliding head O , the beveled reciprocating punch P' , the die P , conformed thereto, and the beveled swage-plate O' , all being arranged and operating with reference to each other, substantially as and for the purposes set forth.
